FREQUENCY CONVERTER

Edward W. Herold, Verona, N. J., assignor to
 Radio Corporation of America, a corporation of
 Delaware

Application June 19, 1937, Serial No. 149,060

7 Claims. (Cl. 250—20)

The present invention relates to a frequency converter circuit for use in a superheterodyne receiver, and more particularly to means for the cancellation or neutralization of space-charge coupling existing between the oscillator and radio-frequency portions of the converter tube.

A frequency converter, sometimes referred to as a pentagrid converter, widely used at present in superheterodyne circuits, consists of a multi-electrode vacuum tube designed to perform simultaneously the functions of a mixer (first detector) tube and of an oscillator tube. During investigations made on frequency converters of the multi-grid type in which the oscillator voltage is impressed on or generated by the first grid (in combination with other electrodes) it was found that a peculiar form of coupling between the oscillator and signal circuits existed which could not be explained by ordinary electrostatic or electro-magnetic effects. Further work indicated that the coupling was caused by a change in the space-charge in the neighborhood of the signal grid as the oscillator voltage went alternately up and down.

An apparently adequate explanation of the effect was given by W. A. Harris in Proc. I. R. E. 23, pg. 279-294, April 1935, where it was also stated that the effect could be neutralized by the connection of a small capacitance from oscillator to signal grids. Later developments have shown that this method of neutralization is inadequate, especially at high frequencies.

An important object of my invention therefore is to provide a frequency converter circuit wherein the space-charge coupling between the oscillator and signal grids may be neutralized more effectively than hitherto possible.

A further object is to effect such neutralization with comparatively simple means. Other objects are to improve generally the operation and efficiency of a frequency converter over a wide range of frequencies.

The novel features characteristic of my invention are set forth with particularity in the appended claims. The invention itself however will best be understood by reference to the following description taken in connection with the accompanying drawing in which,

Figs. 1a, 1b and 2 are certain characteristic curve measurements obtained on the signal grid of a converter tube,

Fig. 3a is a schematic circuit diagram used to explain the action of the space-charge coupling,

Fig. 3b is an equivalent circuit,

Fig. 4 is a frequency converter circuit embodying my invention, and

Fig. 5 is a practical circuit of a frequency converter according to my invention.

I was led to my discovery by an analysis of the high-frequency input admittance data taken on an "RCA-6A8" pentagrid converter with various #1 grid voltages. The data are shown in the form of curves in Figs. 1a, 1b and 2 of the accompanying drawing. Fig. 1a shows the change in #4 grid capacitance from the cold value as the #1 grid voltage is changed. This curve was changed but very slightly as the frequency was changed and so is approximately correct for all frequencies used (i. e., up to 50 mc.).

Fig. 1b shows the #4 grid conductance as a function of the #1 grid voltage. The so-called "cold" and therefore constant conductance of about 12 μ hos was subtracted from the data which shows, therefore, only the conductance caused by electron flow. The curve shown in Fig. 1b was measured at 31.5 mc. At other frequencies, the shape remained the same but the ordinate scale expanded or contracted to a close approximation as the square of the frequency. This is more clearly shown in Fig. 2 which shows the variation with frequency of the #4 grid negative conductance at two of the values of #1 grid voltage used in Fig. 1b.

In Fig. 3a is shown a circuit of a converter tube of the type under consideration. In this diagram, an oscillator voltage $V_o \sin \omega t$ is applied to the grid adjacent to the cathode. It may be mentioned that in the majority of frequency converters of this type it is immaterial as regards this invention whether the oscillator voltage is applied from a separate source as shown or

whether it is self-generated by using the first two grid electrodes of the tube as part of a self-oscillating circuit. The reason for this is that in the majority of tubes the #2 grid is comprised of two, relatively small, electrodes not in the direct path of the main electron stream. Variations in potential of this grid are, therefore, of only minor importance in affecting the currents considered. In Figure 3a, the #2 grid is shown connected to the normal steady d-c potential only. The #3 and #5 grids are screening electrodes and are also connected to a steady supply voltage. The #4 grid, which is the signal grid, is shown connected through an external circuit, consisting of a meter M, to its normally negative bias. If the screening action of the #3 and 5 grids is reasonably effective, the #4 grid circuit inside the tube does not include admittances to any

5 10 15 20 25 30 35 40 45 50 55

other electrodes but the said screening electrodes. As is shown by the data of Figs. 1a and 1b the internal portion of the #4 grid may be represented by a conductance and a capacitance. Calling these g_{g4} and C_{g4} respectively, an equivalent circuit for Fig. 3a is, therefore, Fig. 3b where the #4 grid circuit through the external meter M and applied steady voltage V_{dc} (equal to screen voltage plus signal grid bias as shown in Fig. 3a) is shown completed inside the tube by a conductance g_{g4} and a capacitance C_{g4} .

If the meter M of Fig. 3b is used as an indication of the current flowing in the external signal grid circuit, it is clear that if C_{g4} and g_{g4} were constant, no alternating current would flow. Since g_{g4} is a conductance present only to alternating frequencies (i. e., it is zero at d-c or zero frequency) there would also be no d-c current. This, of course, must be true since the signal grid is biased negatively. In the actual case, however, Figs. 1a and 1b show that C_{g4} and g_{g4} are not constant if the #1 grid voltage is varied. Application of the oscillator voltage $V_0 \sin \omega t$ to the #1 grid causes C_{g4} and g_{g4} to vary up and down periodically in synchronism with the oscillator voltage. As regards the external #4 grid circuit, an a-c current will flow of oscillator frequency as long as V_{dc} is greater than zero. The behavior is analogous to one of a circuit in which C_{g4} is a condenser microphone and g_{g4} is a high resistance carbon microphone, both actuated at oscillator frequency.

In a complete converter circuit, a tuned input circuit is connected in the signal grid in place of the meter M of Figs. 3a and 3b. In this case, the a-c current flowing in this circuit due to the variation of g_{g4} and C_{g4} will set up an alternating voltage of oscillator frequency which is impressed on the signal grid. The voltage set up is especially high when the signal grid circuit is nearly in tune with the oscillator, as it is when a low I. F. is used. The net result is equivalent to a form of coupling between oscillator and signal circuits which is detrimental to good operation.

In brief, it is seen from the above analysis that the variations of oscillator grid potential cause corresponding changes in the signal grid conductance and capacitance. The fluctuations of this conductance and capacitance, acted upon by the d-c potential between the signal and adjacent grids, cause an oscillator frequency voltage to be set up across the signal grid input circuit. The latter voltage causes difficulties in operation including lower conversion gain and troublesome signal grid current due to a-c voltage exceeding the bias. The difficulties are most pronounced when the ratio of signal frequency to intermediate frequency is high.

Quantitatively, inspection of Fig. 1a shows that, for a typical tube, assuming a mean operating #1 grid bias of -8, the #4 grid capacitance change is about $0.06 \mu\text{fd}$ per volt change on #1 grid. At 31.5 megacycles, this corresponds to a susceptance change of $12 \mu\text{mhos}$ per volt change on #1 grid. At the same operating point, Fig. 1b shows that the conductance change, again at 31.5 mc., is about $10 \mu\text{mhos}$ per volt change on #1 grid. From the relative magnitudes of the rates of change of the susceptance and the conductance, it is clear that the conductance change is about equal in importance to the susceptance change. Previous investigators appear to have been unaware of this condition.

Since the rate of change of the susceptance of the #4 grid increases linearly with frequency

while that of the conductance increases with the square of the frequency, as shown by the data of Figs. 1a and 1b, the importance of the conductance change becomes much greater as the frequency is increased. At very high frequencies, the conductance change is the predominant effect, while at low frequencies the susceptance change is most important. Experimental data taken at 20 megacycles showed that the conductance change alone was sufficient to cause serious coupling of oscillator and signal circuits.

As a result of my work, I have found that the phenomenon which occurs in the tube can be completely compensated for by the connection of an admittance from oscillator to signal grids provided this admittance is so chosen as to satisfy certain relations as explained hereinafter.

Previous explanations of the effect attributed it, correctly, to changes in space-charge in the vicinity of the signal grid caused by the variations at oscillator frequency. By this explanation, high-frequency transit time effects are neglected. I have found, however, that at high frequencies, the conductance change mentioned is a transit time phenomenon which is also present and modifies the behavior of the tube markedly so as to make the earlier explanation inadequate. At the same time, the use of a capacitance connected from signal to oscillator grid to mitigate the effect as was done by previous investigators has also been found to be inadequate at high frequencies. Instead, it is found to be desirable to use a more complex admittance; in the usual case it is necessary to add a resistance, preferably in series with the capacitance, in this circuit. The net result is complete elimination of the coupling effect.

In particular, I have found that cancellation or neutralization of the coupling effect described can be accomplished by a connection of a capacitance and a resistance from #1 grid to #4 grid. The C and R combination can be either series or parallel but the former is preferred when operation is to occur over a band of frequencies. Other networks combining resistance, inductance and capacitance can also be used to advantage in particular instances.

To show the neutralization, I have taken data in a circuit similar to Fig. 4. V_1 and V_2 are two vacuum tube voltmeters, the first reading the applied oscillator voltage and the second reading the voltage induced on the #4 grid circuit L_2 , C_2 which is always adjusted so as to give maximum deflection on V_2 for oscillator fundamental frequency. At 20 megacycles with the circuit L_2 , C_2 having a resonant impedance of about 8000 ohms, the following data were taken:

Neutralization	V_1	V_2
None		
Capacitance only (approx. 2 mmfd.)	1.5	3.60
Capacitance and series resistance (approx. 2 mmfd. and 455 ohms)	6.0	3.30
	6.0	0

In the final case of the table, the neutralization was approximately correct over the frequency band from 10 to 25 mc.; the same adjustment of neutralizing condenser and resistor gave a V_2 not exceeding 0.5 volt over the band. For different oscillator voltages, however, a slightly different value of neutralizing admittance was needed. The behavior was qualitatively as predicted by Fig. 1 when it is considered that the #1 grid voltage is altered periodically by the oscillator; a very large V_1 would swing the tube to the upward

curving parts of the ΔC and conductance curve and reduce the neutralization necessary somewhat.

It is clear from the data given above that the use of capacitance neutralization, only, was decidedly unsatisfactory. With the correct resistance-capacitance arrangement, however, it was found that the L_2C_2 circuit was completely independent of the oscillator circuit; tuning C_2 through resonance gave no change in any of the electrode currents or any reaction upon the oscillator voltage. This is in marked contrast to the behavior with capacitance neutralization only.

The explanation of the means by which cancellation is effected by the connection of an admittance from oscillator to signal grid involves the sending of a current through this admittance into the signal grid external circuit which cancels the current in this circuit due to the internal changes of C_{g4} and g_{g4} . It is found that the action of the varying C_{g4} may be counteracted by a constant capacitance connected from oscillator to signal grid. An analysis shows further that the action of the varying g_{g4} may be counteracted at any one frequency by a constant conductance connected from oscillator to signal grid. As the data of Figs. 1 and 2 show, however, the conductance change of g_{g4} varies with the square of the frequency. To adequately cancel the induced effects, the cancelling conductance would have to have a value rising with the square of the frequency. Although more complex circuits can be devised which approximate this characteristic, the simple series connection of a capacitance and resistance can be shown to approximate the condition sufficiently closely, provided the frequency is not too high. As is well known, the effective conductance of a series capacitance C and resistance R is

$$g = \frac{\omega^2 C^2 R}{1 + \omega^2 C^2 R^2}$$

which for small values of ωCR is closely approximated by $g = \omega^2 C^2 R$. Thus a conductance whose value depends approximately (very closely for small values of ωCR) on the square of the frequency is obtained.

At the same time, the effective capacitance of such a series circuit of C and R is approximately constant (again assuming small values of ωCR). The combination, therefore, will adequately cancel the coupling effects over a wide range of frequencies, essentially from 0 frequency to an upper limit imposed by the approximation that ωCR be not too large. In the practical case described by the data of Figs. 1 and 2 this upper limit is about 40 megacycles.

In Fig. 5 I have shown a practical frequency converter system embodying my invention. Briefly, the converter comprises the multi-electrode vacuum tube 10 having the grids marked #1, #2, #3, #4 and #5 interposed in the order named between cathode 11 and anode 12. High frequency signal voltages are impressed on the tunable input circuit 13, the high potential end of which is connected to the #4 grid or signal control grid. Bias for this grid may be obtained from a source of potential connected to the minus side of the grid resistor 14 or from an A. V. C. potential, as well known in the art. The oscillator portion of the converter is constituted by the cathode 11, oscillator grid #1, oscillator anode-grid #2 and the circuits associated therewith. The tuned circuit 13' connected between oscillator grid #1 and cathode 11 determines the fre-

quency of the locally-generated oscillations. Suitable positive potentials are impressed on the oscillator anode-grid #2, screening grids #3 and #5, and the anode 12. Included in the connections from the potential source to said electrodes are the filters 15, 16 and 17, respectively. The interaction within the tube between the locally-generated oscillations and the received signal oscillations results in the production of an intermediate frequency in the output or anode circuit 10 which is tuned to that frequency by the resonant circuit 18. As well known, the I. F. is further amplified and then detected, the resulting audio frequency being fed to a sound reproducing device.

As heretofore explained, in order to compensate for the space charge coupling effects between the oscillator grid and the signal grid, an admittance comprising the series connection of a condenser C and a resistance R is connected 20 between said electrodes as shown. Although I have shown the invention as applied to converter of the type having a self-excited oscillator, it is to be understood that the invention is equally applicable to a converter system wherein 25 an external oscillator is employed in which case the locally-generated oscillations will be applied to the #1 grid, the #2 grid then serving as an additional screening grid which may be connected to the cathode or placed at some suitable 30 d-c potential.

Having thus described my invention, what I claim is:

1. A frequency mixing system comprising a multi-electrode vacuum tube, a signal frequency acting on one of said electrodes and a local oscillator frequency acting on another of said electrodes, said last mentioned electrodes having by reason of their proximity and the potentials impressed thereon undesired interaction, and means for cancelling said interaction of one electrode upon the other, comprising an admittance connected between said electrodes, the admittance consisting of both conductive and susceptive components.

2. In a frequency converter, the combination of a vacuum tube provided with a cathode, an anode and a plurality of control electrodes interposed between said cathode and anode, means for causing a control electrode in proximity to the cathode to oscillate at a definite frequency, means for impressing a signal modulated carrier wave on another of said control electrodes remote from the first control electrode, there being undesired space-charge coupling effects between said control electrodes, and means for compensating for said coupling effects comprising a complex admittance having conductive and susceptive components connected between said control electrodes.

3. In a frequency converter, the combination of a vacuum tube provided with a cathode, an anode and a plurality of control electrodes interposed between said cathode and anode, means for causing a control electrode in proximity to the cathode to oscillate at a definite frequency, means for impressing a signal modulated carrier wave on another of said control electrodes remote from the first control electrode, there being undesired space-charge coupling effects between said control electrodes, and means for compensating for said coupling effects comprising a circuit including capacitance and resistance connected between said control electrodes, the resistance having a value of approximately 75

- 450 ohms and the capacitance a value of approximately 2 micromicrofarads which are effective to compensate for said coupling effects in the frequency range from about 10 to 25 megacycles.
5. 4. In a frequency converter, the combination of a vacuum tube provided with a cathode and an anode, a plurality of control electrodes including a signal grid and an oscillator grid interposed between said cathode and anode, means for causing the oscillator grid to oscillate at a definite frequency, means for impressing a signal modulated wave on the signal grid, the potential variations on the several electrodes being such that the signal grid capacitance is substantially independent of frequency and the signal grid conductance varies substantially as the square of the frequency, and means for compensating for the effects due to said signal grid capacitance and conductance comprising an admittance consisting of both conductive and susceptive components connected between signal and oscillator grids.
10. 5. The invention defined in the preceding claim wherein said admittance is constituted by a series-connected resistance and capacitance, the resistance having a value of approximately 450 ohms and the capacitance a value of approxi-
15. mately 2 micromicrofarads which are effective to compensate for said coupling effects in the frequency range from about 10 to 25 megacycles.
6. In a frequency converter, the combination of a vacuum tube provided with an oscillator section and a signal amplifying section, said sections having undesired coupling therebetween within the tube which increases with frequency, and means for nullifying the effects due to the undesired coupling over a comparatively wide 10 frequency range, said means comprising an external circuit connected between said sections, said circuit including a resistance and a series-connected capacitance.
10. 7. In a frequency converter, the combination of a vacuum tube provided with an oscillator section and a signal amplifying section, said sections having undesired coupling therebetween within the tube, said coupling arising by reason of the signal grid capacitance variation which 20 increases with frequency and the signal grid conductance variation which increases with the square of the frequency, and means for compensating for said capacitance and conductance variations, comprising an admittance connected 25 between said sections, said admittance having both conductive and susceptive components.

EDWARD W. HEROLD.
